VANITY CABINET

Henry M. Snyder, Beverly Hills, Calif.

Application April 18, 1958, Serial No. 50,529

Term of patent 14 years

(Cl. D4—2)

Fig. 1.

Fig. 2.

Fig. 3.

Fig. 1 is a perspective view of a vanity cabinet showing my new design;

Fig. 2 is a front view, in elevation, thereof; and

Fig. 3 is a side view, in elevation, thereof.

The side of the cabinet not completely shown in the drawings, is substantially the same in appearance as the side shown in Fig. 3.

The dominant features of the design reside in the portions illustrated by solid lines.

I claim:

The ornamental design for a vanity cabinet, substantially as shown and described.
